UNITED STATES PATENT OFFICE.

SYLVESTER A. LANGENBAKER, OF SAN FRANCISCO, CALIFORNIA, ASSIGNOR TO MAC-BETH-EVANS GLASS COMPANY, OF CHARLEROI, PENNSYLVANIA, A CORPORATION OF PENNSYLVANIA.

DESIGN FOR A GLASS TUMBLER.

Application filed April 19, 1928. Serial No. 26,377. Term of patent 3½ years.

To all whom it may concern:

Be it known that I, SYLVESTER A. LANGENBAKER, a citizen of the United States, residing at San Francisco, in the county of San Francisco and State of California, have invented a new, original, and ornamental Design for Glass Tumbler, of which the following is a specification, reference being had to the accompanying drawing, forming a part thereof.

Fig. 1 is an elevation of a glass tumbler showing my new design, and Fig. 2 a plan view of it.

I claim:

The ornamental design for a glass tumbler, as shown.

SYLVESTER A. LANGENBAKER.
